Des. 240,097
Patented June 1, 1976

240,097

GARDEN BENCH

Theodor M. Box, 1108 Aileen Road,
Brielle, N.J. 08730

Filed Apr. 10, 1975, Ser. No. 566,796

Term of patent 14 years

Int. Cl. D6—01

U.S. Cl. D6—60

FIG. 1 is a front perspective view of a garden bench showing my design;

FIG. 2 is an end elevation;

FIG. 3 is a plan view;

FIG. 4 is a rear elevation;

FIG. 5 is a section taken along lines 5—5 of FIG. 2.

I claim:

The ornamental design for a garden bench, as shown.
